DESIGN FOR A STAIR TREAD

Harry M. Pryale, Pontiac, Mich., assignor to Baldwin Rubber Company, Pontiac, Mich., a corporation of Michigan

Application September 27, 1937, Serial No. 71,829

Term of patent 7 years

To all whom it may concern:

Be it known that I, Harry M. Pryale, a citizen of the United States of America, residing at Pontiac, in the county of Oakland and State of Michigan, have invented a certain new, original, and ornamental Design for a Stair Tread, of which the following is a specification, reference being had therein to the accompanying drawing, forming a part thereof, wherein; Figure 1 is a top plan view of a stair tread showing my new design; and Figure 2 is an enlarged cross sectional view taken substantially on the plane indicated by the line 2—2 of Figure 1.

I claim:

The ornamental design for a stair tread, substantially as shown.

HARRY M. PRYALE.
